UNITED STATES PATENT OFFICE.

JAMES HEWITT BALDWIN, OF LONDON, ENGLAND.

DEVICE FOR PREVENTING THE FRAUDULENT REFILLING OF BOTTLES AND OTHER CONTAINERS FOR LIQUIDS.

1,324,577.

Specification of Letters Patent.

Patented Dec. 9, 1919.

Application filed May 31, 1918. Serial No. 237,410.

To all whom it may concern:

Be it known that I, JAMES HEWITT BALDWIN, a citizen of the United States of America, and resident at 68 Fenchurch street, 5 London, E. C. 3, England, have invented certain new and useful Improvements in Devices for Preventing the Fraudulent Refilling of Bottles and other Containers for Liquids, of which the following is a specification.

This invention relates to means for preventing the unauthorized or fraudulent refilling of bottles and other containers for liquids, and refers to an improved device of 15 the class in question, which is simple in construction, possesses a comparatively small number of working parts, is not liable to get out of order, effectually prevents refilling whether by the ordinary process of 20 pouring the liquid into the bottle or other container: by immersion of the orifice in the liquid: by the use of an exhaust pump or force pump: or by any other known means usually employed for refilling bottles or 25 other containers furnished with so called "non-refillable" stoppers or attachments. At the same time the device enables the liquid to be readily poured out from the bottle or other container as required.

30 In carrying out my invention, I provide upon or in connection with the pouring orifice of the bottle or other container, a chamber at the bottom of which is located a valve seating, and at the top of which is the actual 35 outlet for liquid. Fitted within the before mentioned chamber so that it is adapted to rest upon the said seating is a buoyant valve and the seating and the valve are so formed that when the valve is resting upon the seating it does not come completely into contact 40 therewith at all points except when pressure is exerted upon the top of the buoyant valve. Means are provided for centering the valve and preventing it coming into contact with 45 the sides of the chamber. Mounted within the chamber above the valve and retained at a suitable distance therefrom is a baffle disk or its equivalent, around or through which the liquid can pass, but which is so 50 located that it prevents the insertion of a tool from the outside for the purpose of tampering with the valve. This baffle disk or its equivalent, and the valve itself are preferably so formed that when the valve

becomes wet and comes into contact with 55 the said disk, it adheres thereto, until it is pulled away with a certain amount of force. A weight is suspended from the valve by a flexible cord or its equivalent. This weight rests in the neck of the bottle or container 60 or within a dependent flange or skirt, the cord being of such length that it suitably limits the motion of the suspended weight while allowing for the free movement of the buoyant valve between the valve seating and 65 the baffle disk or its equivalent. The weight is moreover, so proportioned, formed and arranged, that it enables the liquid to pass freely into the chamber when pouring is to be effected, and at the same time it draws 70 back the valve upon its seating when the bottle or container is tilted back to or beyond the horizontal position.

And in order that my said invention may be clearly understood I will now proceed to 75 describe two methods of carrying the same into effect, by way of example, with reference to the accompanying drawings, in which:—

Figure 1 is a longitudinal sectional elevation of the upper part of the neck of a bottle, in the upright position, with my device fitted thereto.

Fig. 2 is a similar view, with the bottle in the pouring position.

Fig. 3 is a similar view with the bottle in the horizontal position, to illustrate the action of the weight.

Fig. 4 is a similar view with the bottle inverted to illustrate the action of the float or buoyant valve, if the fitting were immersed in liquid.

Fig. 5 shows details hereinafter referred to.

Fig. 6 shows one method of applying my invention to the filling orifice of a petrol can, and to a tube in connection therewith for the admission of air.

Figs. 7 and 8 show in elevation and plan respectively a detail hereinafter referred to.

The same letters and numerals of reference are employed to denote the same parts in all the views.

Referring to the form of the device shown in Figs. 1 to 5 *a* is the neck of the bottle. *b* is a cylindrical fitting forming a shallow chamber provided with a valve seating *c* and vertical ribs *d*. This fitting is made

with a downwardly extending stepped boss *e*, the whole fitting resting at the top of the neck of the bottle with the stepped boss *e* projecting downward, a suitable washer *f* being interposed between the fitting and the top of the neck of the bottle, before the metallic sleeve effecting the attachment is spun into position.

The valve seating *c* is made so that it is

10 not perfectly even. In the present case it is provided with two diametrically opposite raised portions *c*¹, as shown greatly exaggerated at Fig. 5, for the purpose hereinafter fully explained.

15 *g* is a flexible cork valve of suitable size to rest upon the seating and to move with sufficient freedom between the ribs *d*. This valve has suspended therefrom by means of a flexible cord *h* a weight *k*, which is of sub-

20 stantially conical form provided with upwardly extending radial arms *m* between which are arched spaces or channels *p*.

25 *g* is a disk provided with a number of arch-shaped slots *q*² and a central portion *q*¹ of about the same size as the cork valve *g*.

30 This disk is adapted to rest upon the top of the fitting *b* as shown. *r* is an outer casing provided with a pouring orifice *s*. This casing is adapted to inclose the fitting *b* and to rest upon the washer *f* and is held in position by means of the sleeve which is spun over it and the neck of the bottle in the ordinary well known manner, thus holding all the parts securely in position.

35 I will now explain the way in which the device operates.

Referring first to Fig. 1, it will be seen that the valve *g* is held in position upon the seating *c* under the pull of the suspended weight, *k*.

40 If the valve seating were perfectly flat, as soon as it and the underside of the valve *g* became wet, the air would be excluded and would be unable to pass between them and the valve would adhere to the valve seating. The outer air being thus unable to enter the bottle, and the pressure outside being greater than the pressure inside, it would be possible even to invert the bottle and to have the entire weight of the liquid pressed down upon the valve *g* without the said valve becoming separated from the seating. It would consequently be impossible to pour from the bottle unless the adhesion were broken.

45 In order to weaken the adhesive forces and to secure the necessary balancing of air pressure, I therefore incline the seating *c* at a very slight angle, as already explained.

50 Supposing now that the bottle is tilted into the position shown at Fig. 2. The stream of liquid attempting to find its way out pushes on the back of the buoyant valve *g* and as with the construction shown, the 55 forces making for adhesion between the

valve and the valve seating are not so great as the forces operating against it, the valve pushed forward and the liquid finds its way through the spaces *p*, past the valve *g*, between the valve and the fitting *b* through the spaces between the ribs *d*, and through the slots *q*² to the pouring orifice *s*.

Owing to the limitations of form imposed upon devices of this general character, it is very difficult to prevent some accumulation of liquid within the chamber, when pouring, and when such accumulation takes place, owing to the buoyancy of the valve *g* and the force of the incoming currents of air, there is a tendency for the valve to close 75 upon the valve seating and to shut off entirely or greatly impede the flow of liquid. This tendency is counteracted in the following manner. The shape and size of the part *q*¹ of the plate *q* closely approximate to 80 that of the valve *g* and largely or entirely protects it from the force of the incoming current of air. As the bottle is tilted into the pouring position, what is normally the upper surface of the valve *g* comes into contact with what is normally the under surface of the plate *q*, and the parts being wet 85 there is a tendency to adhesion, which tendency is greatly augmented by the pressure of the air in the chamber, and (or) the pressure of the outflowing liquid upon what is normally the under surface but in the pouring position the upper surface of the valve *g*.

The forces thus brought into play are 90 sufficiently strong to overcome the buoyancy of the valve and any possible pressure of incoming air against which the valve *g* is protected by the plate *q*, as just explained.

The whole result is that the liquid is 95 found to pour out very freely and in a most satisfactory manner, even when the bottle is inverted.

On the other hand, as soon as the bottle is tilted back to or beyond the horizontal position, as shown at Fig. 3, which would 110 be necessary in any attempt to re-fill in the ordinary way the end of one of the radial arms *m* comes against the bottom of the fitting *b* and the weight exerts a lever like action which pulls the valve upon the 115 seating *c*.

The flexibility of the valve *g* is so proportioned that any attempt to force in liquid will be sufficient to cause the valve to adhere to all parts of the seating and to 120 close the ingress of liquid.

When the bottle is inverted, as shown at Fig. 4, and the fitting immersed in liquid, it is still impossible to refill the bottle, as the buoyancy of the valve causes it to 125 rise to the top of the chamber and any attempt to force in liquid will in addition make the valve adhere closely to the seating, thus preventing the passage of the liquid.

In practice, I prefer to make all the parts of the device, except the buoyant valve *g*, washer *f* and the cord, of porcelain or some analogous material where the fitting is to be applied to a bottle for containing spirits or the like.

I will now consider the adaptation of my invention to the pouring orifice of a petrol can, as illustrated in Figs. 6, 7 and 8.

10 10 is the nozzle of the can, which is preferably made somewhat larger than is usual, and may be provided with a downwardly extending flange or skirt 11.

15 13 is a fitting which corresponds with the fitting *b* in the previous construction, and which is adapted to slide into and rest in the nozzle 10 being flanged over at the top at 14, to rest upon a step or shoulder formed in the nozzle as shown.

20 The fitting 13 is provided with ribs *d*, a valve seating *e*, a buoyant valve *g* and a weight *k* carried by a cord *h*, as already explained.

When the fitting 13 has been placed in position, the baffling device shown in detail at Figs. 7 and 8 is inserted.

This consists, in the present case, of a ring plate 15, carrying a circular disk or plate 16 by means of downwardly extending arms 30 17, pouring orifices 18 being left for the passage of the liquid.

The flange 14 and the ring 15 are sufficiently small to pass through the outer orifice which is turned or beaded over at 19.

35 When the ring 15 is placed in position with the edges coming below the projecting beading 19, the metal is spun out or otherwise treated to hold the device in position, as indicated by dotted lines at Figs. 7 and 40 8, and as seen clearly at Fig. 6.

When it is required to re-fill the can, when it is returned to the works, the ring plate 15, is levered out by means of a suitable tool, and a fresh plate is required, 45 after the can has been re-filled, which is done by simply lifting out the fitting 13 with the valve and associated parts, this fitting being replaced after the filling has been effected.

50 I prefer to combine, with the filling device, a means for enabling air to pass to the top of the can, as pouring takes place, and one method of effecting this is shown in Fig. 6.

55 It will be seen that the nozzle 10 is cut away at 20. 21 is a tube which is flattened out at 22, and soldered or otherwise suitably attached to the fitting 13, so that it can be removed therewith when required.

60 The tube 21 extends downward to within a short distance of the bottom of the can, and may be fitted at the lower end with a small "non-refillable" fitting indicated in section at 23.

65 In this case the edge of the ring 15 is

cut away where it comes opposite to the flattened portion 22 of the tube 20 but the tube opens above the ring 15.

With this arrangement, pouring may be easily effected, as the petrol passes out through the principal fitting, while the air passes in by the tube 20. The fitting 23 is intended to prevent the possibility of re-filling the can by passing petrol down the tube intended for the passage of air. 75

I prefer to provide a single cap, for covering in the orifice for pouring and the top of the tube for the admission of air.

It will of course be understood that the details of construction may be varied without departing from the principle of my invention. 80

In some cases I may dispense with the retaining action of the disk above the valve, relying upon the forward rush of the liquid to counteract the buoyancy of the valve, but in all cases I provide above the valve means for preventing tampering with the said valve through the outlet orifices. 85

While the invention has been shown and described in its preferred form, it will be understood that changes and variations may be made with respect to certain of the specific structures shown and described, and that the invention is not therefore limited 95 to the precise structure illustrated.

What I claim and desire to secure by Letters Patent of the United States of America is:—

1. In a device of the class described, the combination of a container having a pouring orifice, a chamber, a valve seat at the bottom of the chamber, a pouring outlet at the top of the chamber, a buoyant valve adapted to seat on the valve seat and to move vertically in said chamber, means for preventing contact between the sides of the valve and the inner surface of the chamber, means for minimizing adhesion between the underside of the valve and the valve seat, 105 and means between the pouring orifice and the valve for preventing tampering with the valve.

2. In a device of the class described, the combination with a container having a pouring orifice, a chamber, a valve seat at the bottom of the chamber the upper surface of the valve seat having portions in different horizontal planes, a buoyant valve of a material of such flexibility that when pressure is applied to its top it will seat on the entire surface of the seating, said valve being adapted to move vertically in the chamber, means for preventing contact between the sides of the valve and the inner surface of the chamber, and means between the pouring orifice and the top of the valve for preventing tampering with the valve. 120

3. In a device of the class described, the combination of a container having a pour- 130

1. In a device of the class described, the combination of a container having a pouring orifice, a chamber, an outlet opening at the top of the chamber, an inlet orifice at the bottom of the chamber around which is a valve seat, a buoyant valve adapted to move vertically within the chamber, means for preventing contact between the sides of the valve and the inner surface of the chamber, means for preventing adhesion between the underside of the valve and the valve seat, a weight secured to the valve by a flexible cord so as to depend therefrom, and means between the pouring orifice and the top of the valve for preventing tampering therewith.
2. In a device of the class described, the combination of a container having a pouring orifice, a chamber, a valve seat at the bottom of the chamber, a pouring outlet at the top of the chamber, a buoyant valve adapted to seat on the valve seat and to move vertically in said chamber, means for preventing contact between the sides of the valve and the inner surface of the chamber, means in the chamber to which the valve adheres when wet to prevent the valve from floating against the seat when there is liquid in the chamber, and means for breaking the adhesion.
3. In a device of the class described, the combination of a container having a pouring orifice, a chamber, a valve seat at the bottom of the chamber, a pouring outlet at the top of the chamber, a buoyant valve adapted to seat on the valve seat and to move vertically in said chamber, means for preventing contact between the sides of the valve and the inner surface of the chamber, means in the chamber to which the valve adheres when wet to prevent the valve from floating against the seat when there is liquid in the chamber, and a weight secured to the valve by a flexible cord so as to depend therefrom and pull the valve to its seat.
4. In a device of the class described, the combination of a container having a pouring orifice, a chamber, an outlet opening at the top of the chamber, an inlet orifice at the bottom of the chamber around which is a valve seat, a buoyant valve adapted to move vertically within the chamber, means for preventing adhesion between the sides of the valve and the inner surface of the chamber, means for preventing adhesion between the underside of the valve and the valve seat, a cone shaped weight secured to the valve by a flexible cord so as to depend therefrom, said weight being provided with radial arms provided with openings for the passage of liquid therebetween, the ends of said arms acting to exert a levering action to seat the valve when the container is at or above horizontal position, and means between the pouring orifice and the top of the valve for preventing tampering with the valve.
5. In a device of the class described, the combination of a container having a pouring orifice, a chamber, a valve seat at the bottom of the chamber, a valve seat at the top of the chamber, a buoyant valve adapted to move vertically within the chamber, means for preventing contact between the sides of the valve and the inner surface of the chamber, means in the chamber to which the valve adheres when wet for preventing the valve from floating to the valve seat when there is liquid in the chamber, a weight secured to and suspended below the valve for pulling the valve back to its seat, a tube for the admission of air to the container, and a valve in the tube acting to prevent refilling therethrough.
6. In a device of the class described, the combination of a container having a pouring orifice, a chamber, a valve seat at the bottom of the chamber, a liquid outlet at the top of the chamber, a buoyant valve arranged to seat upon the valve seat and to move vertically in the chamber, means for preventing contact between the sides of the valve and the inner surface of the chamber, means for minimizing the adhesion between the underside of the valve and the valve seat, means in the chamber with which the valve may adhere when wet to prevent its floating the valve seat when there is liquid in the chamber, and means secured to the valve for breaking the adhesion.

JAMES HEWITT BALDWIN.
